Primary Examiner — Brett Miller*Assistant Examiner* — Sara Michie Pottenger(74) Attorney, Agent, or Firm — Condo Roccia Koptiw LLP(57) CLAIM

The ornamental design for a holder for a post as shown and described.

DESCRIPTION

FIG. 1 is a front view of a holder for a post according to the present invention;

FIG. 2 is a rear view of FIG. 1;

FIG. 3 is a side view of FIG. 1;

FIG. 4 is a side view of FIG. 1;

FIG. 5 is a top view of FIG. 1;

FIG. 6 is a bottom view of FIG. 1; and,

FIG. 7 is a top perspective view of FIG. 1.

The broken line showing is included for the purpose of illustrating unclaimed subject matter and forms no part of the claimed design.

The shade line showing is included for the purpose of illustrating contour and not surface ornamentation.
